ERASER HOLDER FOR PENCILS

Anthony Scharf, Chicago, Ill.

Application March 13, 1940, Serial No. 323,717

5 Claims. (Cl. 120—38)

This invention relates to eraser holders or ferrules used in conjunction with lead pencils having a wooden body or the automatic type known as a lead clutch holding pencil.

- 5 One of the main objects of my invention is to provide a ferrule which has means for protecting the surface being erased when the eraser is worn down to the level or top edge of the ferrule holding member.
- 10 Another object of my invention is to provide reinforcing means to the top edge of a ferrule member in order to strengthen the same and make it more rigid so as to resist breakage.

Another object of my invention is to provide 15 eraser holding ferrule means which is attachable to a wood pencil or an automatic pencil and which has resilient spring holding means adapted to hold adjustably, removably, and securely an eraser in a set or fixed position.

20 Another object of my invention is to provide resilient flexible prong means for adjustably and securely holding an eraser in a fixed position within an automatic pencil, the said prong means being held frictionally in contact with the eraser 25 by virtue of sleeve means or recess means in the end of a pencil.

Another object of my invention is to provide in 30 addition to the merits and advantages heretofore enumerated in eraser holding ferrules, an article which is not more expensive to manufacture than the present ferrule member.

Another object of my invention is to produce a simple, practical, efficient, article of the character to be described which is durable and also 35 economical to manufacture in quantity production.

Other features, objects, and advantages to be attained as a result of the structure herein provided will be readily apparent, upon reading further 40 the description in connection with the drawing forming a part of the application in which like numerals are used to designate like parts and in which:

Fig. 1 is a front elevation of an ordinary lead 45 pencil with my invention attached thereto.

Fig. 2 is a fragmentary and enlarged cross-sectional view of one form of my invention taken on the line 2—2 of Figure 1.

Fig. 3 is a fragmentary and enlarged cross-sectional view of a modified form of my invention.

Fig. 4 is a transversal cross-sectional view on the line 4—4 of Figure 3.

Fig. 5 is a longitudinal cross-sectional view of 50 a modified form of my invention used in connec-

tion with an automatic type of pencil or in connection with a telescopic sleeve holding means for more effective operation, and which may be attached to the ordinary wood lead pencil.

Before explaining the structure of my invention, I feel that it is advisable to elucidate first upon the reasons why I have created this invention. Being a frequent user of pencils in my work, and inasmuch as I have to do considerable erasing, I have found that erasers worn down to 10 the edge of the ferrule cause considerable damage to the material upon which the eraser is used.

The erasers in due course of time become worn, and when they are worn close to the raw edge or 15 unfinished edge of the present ferrules which are provided for the purpose of holding erasers on the ends of pencils, the raw edge will sometimes cause the material being erased or paper being erased to be scratched and torn. Furthermore I have 20 had occasion to observe that a great many individuals have a habit of chewing upon the end of the pencil which holds the eraser, in which event the edge of the ferrule which is not very strong is bent into irregular shape, whereby sometimes 25 breaks appear in the material and very sharp points are thus formed which have a tendency to tear the paper.

Such individuals, who have a habit of chewing pencils find that sometimes, because of this habit, 30 their lips become scratched or irritated by the edge of the ferrule having become very erose and rough. It is with these two situations that I, myself, have had to contend, and for this purpose I have created the improvement comprising my 35 invention.

Referring more particularly to Figure 1, 6 generally designates a pencil, and 7 the ferrule attached to an ordinary lead pencil, whereas 11 40 designates the eraser used for purposes of erasure and making corrections.

Referring to Figure 2, where one form of my invention is illustrated, 7 generally designates my invention which is a sleeve or shell made of sheet metal or of any other suitable material, and which 45 is attached to the wooden pencil 9 at a point indicated by the numeral 8, this being usually accomplished by a piercing punch operation, in order to break thru the material from which the ferrule 7 is made up, thus wedging it into the 50 wood of the pencil body 9.

This leaves a portion above the pencil end 10 vacant, so as to receive the eraser 11. Now, my 55 improvement to the construction is provided by the formation of a bead 12 on the top edge of the 60

ferrule, which as a standard product, at the present time, is made with the raw edge or sharp edge of the material from which the ferrule is made to end up abruptly and as indicated by the 5 dotted line 30.

The top edge, as can be seen, would thus be very sharp and the outside edge when the eraser is worn down to the level of the top of the edge 30, would thus tend to tear paper or material 10 upon which erasures are to be made.

Altho it can be seen, by examining drawing Figure 2, why the arrangement or structure as indicated at 30 would be easily broken by biting or if accidentally stepping thereon, thus subjecting the 15 material upon which erasures are made to even greater damage, tearing and destruction.

My improvement comprises the bead 12 which converts the raw edge 30 by folding over the material and into the bead formation 12, which 20 operation can be produced without any additional expense by modifying the dies which make such ferrules so that simultaneously with the operation of making the ferrule, the beading can be done without any extra cost and without adding 25 any extra material to the structure; yet deriving two decided advantages in that a stronger top edge is provided by the bead 12 as a protection at such time when the eraser is worn down to the dotted position or level 29, or 30 when the top surface of the bead 12 should touch the paper while erasing, in that event the round smooth beaded portion would, in fact, burnish over the portion of the paper, thus if changes or alterations have to be made the fibers of the 35 paper having been burnished will provide a smooth surface susceptible of receiving ink or pencil corrections.

In Figure 3, the construction is the same as in Figure 2 wherein the eraser 11 is secured to the 40 bead 12, my invention being generally designated 13 and which, however, is secured by the pierced portions 14 to the pencil 9 in the same manner as explained in Figure 2.

The improvement, in this modification, is the 45 arrangement whereby I provide at least three prongs which emanate from drilled portions 16 and the recessed portion 20 and thus may be caused to flex inwardly or outwardly from the anchorage point at the base wherein the relief 50 holes 16 are provided.

The prongs 17 are approximately shaped as indicated, being coiled over or beaded over as indicated at 19 in order to remove any rough edges which might interfere with the handling 55 of the pencil or instrument, and they are provided with a straight portion toward the top which is preferably knurled as indicated at 18, and which is adapted to grip the eraser 11 substantially so that the eraser will be held rather 60 tightly by the friction exerted by the prongs 17 by virtue of the spring action of the prongs 17 and the knurled or roughened surface 18.

It would be possible, with this arrangement, to take hold of the exposed portion of the eraser 65 11 and pull it outwardly, whereas by virtue of the spring tension of the portions 17 and the gripping surface 18, the eraser could not be pushed backward during the erasing procedure, the tendency of the prongs being in an inward direction 70 would have a tendency to sustain the eraser in any position placed once it is pulled out or upwardly.

If the eraser is pulled too great a distance outward when adjusting the eraser for wear, then 75 by actuating the prongs with a pin or other

pointed instrument, the eraser may be pushed downwardly and then readjusted to a suitable height or operating position.

In like manner the bead 15 is provided for protection from destruction by biting or accidentally dropping or stepping on the pencil, and also providing a smooth burnishing edge for erasure made on papers or other similar material, thus providing a clean and fresh surface for making changes or alterations on such erased portions. 10

Figure 4 further indicates, in exaggerated detail and enlarged form, the method in which the three prongs 17 hold the eraser in position against rotation and against downward movement. The 15 numeral 24 indicates the compression to which the eraser 11 is subjected in order to effect a firm grip of the same.

In Figure 5, I show an arrangement which is 20 preferably adaptable for the hollow sleeve or recessed portion in an automatic clutch pencil indicated by the numeral 21. However, this modified form for gripping the eraser more substantially and more effectively may also be utilized on an ordinary wood lead pencil by adding 25 the extra sleeve element 21. In an automatic pencil that portion is an extension of the body mechanism of the pencil, and the eraser 11 may be held in my ferrule arrangement indicated, and generally designated by 27. 30

In this view my holder is beaded at the top the same as heretofore mentioned and for the same purpose and reasons, and is provided with three prongs 25 operating in the recesses 26 with relief holes 24 in order to obtain ideal spring action 35 of the spring portions 25.

The inner portion of the ferrule 22 is adapted to receive the eraser 11 and the lower portion is beaded over inwardly as indicated at 23, so that, if necessary, the pencil itself may be inserted thru the opening provided by the bead 23 at the lower portion and the eraser ejected or adjusted for wear; and in like manner, when the eraser has been worn down to the top surface of the bead 27, the bead will serve the purpose of burnishing and protecting the surface as well as the ferrule itself from accidentally being destroyed when dropped or from chewing it. 40

I believe, I have described, rather succinctly the nature of the improvement added to the standard structure of an eraser holding ferrule to be attached to the end of a pencil or other similar instruments, and, I believe, that I have described in detail the advantages and features to be derived from my invention so that those familiar with the art will have no difficulty in grasping the importance of my invention. 50

Altho, I have shown preferred forms of my invention yet I feel that it is susceptible of many alterations, modifications, and improvements, and hence I hereby reserve the right to all such modifications, alterations, and improvements which may result from the design, engineering, development, and manufacture of my invention in accordance with the spirit and scope thereof, and the purview of the foregoing description taken in connection with the drawing comprising a part of this application; my invention to be limited only to the subjoined claims. 60

Having thus described my invention what I claim as new and desire to secure by Letters Patent 70 is:

1. In an article of the character described, eraser holding means provided with bead means located on the edge of the eraser holding portion from which the operative portion of an eraser 75

projects, the said bead means produced by spinning outwardly the edge on which it is formed.

2. In an article of the character described, eraser holding means provided with bead means located on the edge of the eraser holding portion from which the operative portion of an eraser projects, the said bead means produced by spinning outwardly the edge on which it is formed, and prong means formed integrally with said eraser holding means adapted to hold in operative position frictionally and adjustably an eraser member, the said prong means provided with a beaded portion at its free end, and a knurled surface portion intermediately positioned between the free end and the base of the said prong means.

3. An article of the character described, comprising eraser holding means provided with bead means located on the edge of the eraser holding portion from which the operative portion of an eraser projects, the said bead means produced by spinning outwardly the edge on which it is formed, prong means formed integrally with said eraser holding means adapted to hold in operative position frictionally and adjustably an eraser member, the said prong means provided with a beaded portion at its free end, and a knurled surface portion intermediately positioned between the free end and the base of the said prong means and an eraser member frictionally and adjustably secured to the said eraser holding means so that the effective operative portion of said eraser member projects beyond the said bead means.

4. An article of the character described comprising, a ferrule member having a multiplicity of piercing perforations adapted to be attached to the end of a pencil leaving a vacant portion extending beyond the end of said pencil, the said ferrule member further provided with bead means on the free end thereof, the said bead means produced by spinning outwardly the edge on which it is formed, resilient eraser holding means comprised of a number of prong holding portions adapted to hold an eraser in operative position, frictionally and adjustably, the said prong means provided with a beaded portion at its free end, and a knurled surface portion intermediately positioned between the free end and the base of the said prong means.

5. In combination, sleeve means, and a ferrule member telescopically secured to the said sleeve means, the said ferrule member provided with bead means located on the edge of the eraser holding portion from which the operative portion of an eraser projects, the said bead means produced by spinning outwardly the edge on which it is formed and prong means formed integrally with said ferrule member adapted to hold frictionally and adjustably the said eraser, the said prong means provided with a beaded portion at its free end, and a knurled surface portion intermediately positioned between the free end and the base of the said prong means. 30
